UNITED STATES PATENT OFFICE.

ADAM COCHRANE, OF LOWELL, MASSACHUSETTS.

ELECTRIC STOP-MOTION FOR MOTORS AND SIGNAL FOR THE SAME.

No. 897,350.

Specification of Letters Patent.

Patented Sept. 1, 1908.

Application filed March 21, 1908. Serial No. 422,415.

To all whom it may concern:

Be it known that I, ADAM COCHRANE, a citizen of the United States, residing at Lowell, in the county of Middlesex and Commonwealth of Massachusetts, have invented 5 a certain new and useful Improvement in Electric Stop-Motions for Motors and Signals for the Same, of which the following is a specification.

This invention relates to electric stop-motions for motors and signals for the same.

This invention is applicable to any engine or motor driven by the pressure of a fluid and capable of being stopped by cutting off the 15 supply of fluid, as by a gate or valve.

It is to shut off the flow of steam to a steam-engine or of water to a water-wheel by the closing of an electric circuit when the engine or wheel approaches too near a dangerous 20 rate of speed. In these cases the current is furnished by a storage battery, and there is no means other than actual test of knowing whether the battery is in working order and it has many times happened that where the 25 engineer has attempted to operate a manual circuit-closer with which such circuits are commonly provided he has found that there was no current and that therefore the automatic stop-motion was inoperative and useless. 30

One object of this invention is to furnish a constant signal, while the motor is running, which shall indicate at once to the person in charge of the motor that the current is operative and ready for use, and of course, the absence of the signal would in itself be a signal to indicate an absence of current.

In carrying out my invention, I have arranged upon the shaft of a centrifugal governor a dynamo which rotates therewith and furnishes a constant current when the motor is in operation through a closed circuit in which is included a suitable signal or indicator, preferably an incandescent light, 45 which may be arranged upon the case of the governor or in any place where it will be seen at all times by the person in charge of the motor. I also provide two open circuits in one of which is arranged a manually-operated 50 circuit-closer, to be used in case of apparent danger of any kind which may be averted by stopping the motor and in this circuit is included an electric coil, as a solenoid or electro-magnet which is arranged to operate a 55 shut-off, as a valve in the pipe which conducts the steam, water or other fluid to the

steam cylinder or analogous part of the motor.

The centrifugal governor shown in the accompanying drawing may be the usual governor of a steam engine or other motor or may be a supplementary governor driven from any suitable part of the motor. 60

In the accompanying drawing I have shown in central longitudinal section the case of 65 a governor and a dynamo, the armature of which is mounted on the shaft of the governor; also a central vertical section of a part of the pipe which conducts the motive power to the motor; a shut-off valve; also in elevation a solenoid arranged in an open circuit with a manually-operated circuit-closer and in another open circuit closed by the movement of the governor. 70

A indicates the case or frame of the governor; B, a centrifugal governor; b, its springs; b¹, its weights or balls; b², its fixed head; b³, its movable head drawn towards the fixed head by the spreading apart of the governor-balls; b⁴, the governor-shaft which 75 supports all the other parts of the governor and turns in the case or frame A in which said shaft is journaled; b⁵, a pulley fast on the governor-shaft and driven by a belt (not shown) in the usual manner; all these 80 parts being of the usual construction and operation. 85

A feed-pipe C of any suitable construction and provided with a valve-seat c, conducts the motive power to the engine-proper, as 90 from the boiler to the cylinder of a steam-engine. A suitable valve D is arranged to slide in an enlargement or valve-case c¹ of the pipe C and is normally held open by the pressure of the fluid, as steam, passing 95 through said feed-pipe in the direction indicated by the arrows.

A suitable dynamo E of any usual construction is mounted upon the governor-shaft b⁴ concentrically therewith and revolves therewith at all times when the motor is in operation. One pole of the dynamo is connected to the solenoid F by the wire f and the other pole of said dynamo is connected by the wire f¹ to a conducting pin e¹ secured in the metallic or conducting frame e of said dynamo, and another wire g leads from said pin to a push-button G or other normally open circuit-closer, said push-button being connected by a wire g¹ to another wire f² which connects the other end of said solenoid to a contact-screw f³ sup- 100 105 110

ported on a bracket f^4 secured to but insulated from (at f^5) the case A.

When the governor has attained such a speed as to bring its movable head b^3 or the 5 flange b^6 which projects from said movable head into contact with the screw f^3 , a circuit is closed from the dynamo through the wire f , the solenoid F, the wire f^2 , contact-screw f^3 , movable governor-head b^3 and through 10 the governor-frame and dynamo-frame, pin e^1 and wire f^1 to the dynamo.

When the circuit-closer G is closed by hand, the current passes from the dynamo to the solenoid by the wire f and from the 15 solenoid by the wires f^2 g^1 , pin e^1 and wire f^1 back to the dynamo. The closing of either of these circuits excites the solenoid and pushes its core d which is a continuation of or rigidly connected to the stem of the valve 20 D in such a manner as to crowd said valve upon its seat c and shut-off the motive fluid. The valve D may be opened by hand or by the pressure of the motive fluid and will be kept open by said pressure when neither of 25 the normally open circuits above described is closed.

A signal which I have represented as an incandescent light H is supported in any convenient place where its absence would be 30 noted by the person in charge of the motor and is connected by wires h h^1 to opposite poles of the dynamo and is normally in circuit, so that this light should be glowing constantly and when it fails it indicates that 35 its own circuit is broken or that there is some trouble with the dynamo or with its driving mechanism, as that the belting or gearing is broken.

The improvement herein described will 40 prevent much loss and damage to persons and property heretofore caused by the bursting of fly-wheels due to excessive speed of the same, an occurrence so common that companies have been formed which make a 45 specialty of insuring against such accidents.

I claim as my invention:—

1. The combination of a centrifugal governor, a dynamo-electric machine, mounted

on said governor and rotating therewith, a shut-off, a normally open electric circuit, in 50 which said dynamo is included, means for operating said shut-off included in said circuit, and means operated by said governor for closing said circuit when said governor attains a predetermined speed. 55

2. The combination of a centrifugal governor, a dynamo-electric machine, mounted on said governor and rotating therewith, a shut-off, a normally open electric circuit, in 60 which said dynamo is included, said shut-off being provided with a stem of magnetizable material, a solenoid also inclosed in said circuit and surrounding said stem, and means operated by said governor for closing said circuit to operate said shut-off when said governor attains a predetermined speed. 65

3. The combination of a centrifugal governor, a dynamo-electric machine, mounted on said governor and rotating therewith, a shut-off, a normally open electric circuit, in 70 which said dynamo is included, means for operating said shut-off included in said circuit, and means operated by said governor for closing said circuit when said governor attains a predetermined speed, a closed electric circuit in which said dynamo is also included, and a signal arranged in said closed circuit. 75

4. The combination of a centrifugal governor, a dynamo-electric machine, mounted 80 on said governor and rotating therewith, a shut-off, a normally open electric circuit, in which said dynamo is included, means for operating said shut-off included in said circuit, and means operated by said governor 85 for closing said circuit when said governor attains a predetermined speed, a closed electric circuit in which said dynamo is also included, and an incandescent lamp arranged in said closed circuit. 90

In witness whereof, I have affixed my signature in presence of two witnesses.

ADAM COCHRANE.

Witnesses:

ALBERT M. MOORE,
ALBERT HALLOWELL.

Correction in Letters Patent No. 897,350.

It is hereby certified that in Letters Patent No. 897,350, granted September 1, 1908, upon the application of Adam Cochrane, of Lowell, Massachusetts, for an improvement in "Electric Stop-Motions for Motors and Signals for the Same," an error appears in the printed specification requiring correction, as follows: In line 16, page 1, after the word "is" the word *common* should be inserted; and that the said Letters Patent should be read with this correction therein that the same may conform to the record of the case in the Patent Office.

Signed and sealed this 27th day of October, A. D., 1908.

[SEAL.]

C. C. BILLINGS,
Acting Commissioner of Patents.
